UNITED STATES PATENT OFFICE

2,684,245

GOLF HOLE PROTECTOR

Louis Jacoby, Dallas, Tex.

Application October 20, 1951, Serial No. 252,330

5 Claims. (Cl. 273—34)

1

United States Golf Association regulations require that putting cups be set one inch below the surface of the putting green, and the principal object of this invention is to protect and maintain the wall of the hole in the putting green above the putting cup.

Further objects and advantages of the invention will appear as the disclosure proceeds and the description is read in connection with the accompanying drawing, in which

Fig. 1 is a perspective view of a familiar putting green;

Fig. 2 is a section on the line 2—2 of Fig. 1;

Fig. 3 is a vertical section on the line 3—3 of Fig. 2;

Fig. 4 is a plan view looking into the putting cup;

Fig. 5 is a section corresponding to Fig. 3 with the protecting device just above the cup;

Fig. 6 is a plan view of the body portion of the protecting device;

Fig. 7 is a side elevation of the same;

Fig. 8 is a vertical section through another embodiment of the invention;

Fig. 9 is a plan view of Fig. 8;

Fig. 10 is a vertical section through still another embodiment of the invention; and

Fig. 11 is a plan view of Fig. 10 with the parts broken away.

The reference numeral 10 indicates a putting green equipped with a familiar metal putting cup 11 having a pole socket 12 secured to it by diagonal braces 13.

The embodiment shown on sheets 1 and 2 of the drawing includes a generally cylindrical body portion 14 having a rounded or spherical bottom 15 and enlarged at the top to provide a cylindrical wall or flange 16 to fit against the wall 17 in the earth above the cup 11.

The cylindrical body 14 fits loosely in the cup 11 as shown in Fig. 3, and the cylindrical wall 16 overhangs the top of the cup.

At opposite sides the body is slit, as indicated at 18, to provide for expansion and contraction.

The split flange 16 in effect becomes two movable curved members adapted to fit and press against the earth wall 17 and tend to constantly maintain it. A conical expander 19 has a cylindrical flange 20 adapted to be forced between the curved members and fit them to the earth wall.

The expander has a disk-like bottom 21 provided with an opening to receive a reduced portion 22 of the staff 23 to which it is made fast by a ring 24 and a pin 25.

2

The bottom of the staff has a ferrule 26 to fit within the pole socket 12, and above the ferrule is a reduced portion 27 which passes through an opening 28 in the disk-like seat 29 in the bottom 5 of the body 14. This provides a limited axial movement between the staff and the body portion corresponding to the appropriate movement of the expander in spreading or releasing the curved member 16.

10 A helical spring 30 compressed between the expander and the bottom of the body urges the expander upwardly toward the position shown in Fig. 5, but is overcome by the weight of the staff and the flag pole when in the cup.

15 When the flag is to be set, the device is put in the position indicated in Fig. 5 and lowered into the cup, the rounded bottom portion 15 of the body serving to center it in the descending movement and to prevent injury to the wall 17. As the rounded bottom 15 comes against the upper end of the socket 12, the weight of the staff and flag pole will compress the spring 30, and the expander will move the curved portions of the flange 16 outwardly against the earth wall 17, in which 20 position they define a cylinder 4 1/4" in diameter, the size of the regulation hole.

25 When the flag is to be removed, the staff 23 is raised, taking the expander upwardly toward the position shown in Fig. 5, the effect of which is to relieve the pressure on the portions of the flange 16 and permit them to collapse or contract. Only a small amount of movement is required to fit those portions of the flange to the wall 17 above the cup or to loosen them from the wall so as 30 to permit the device to be withdrawn.

35 The lost motion connection between the staff and the bottom of the body 14 provides for the appropriate movement of the expander before the body has to start upwardly.

40 The contracting or collapsing of the flange 16 and corresponding portions of the body 14 is provided by the resiliency of the material, which may be of great variety since the shape will naturally give resistance to permanent set.

45 The staff 23 may be one with a flag pole, but as here shown it is provided with a long pole socket 31 adapted to tightly receive a ferrule 32 on a flag pole 33. In this way, the protecting device forms an article of manufacture that can be readily supplied for use with standard cups and pole equipment.

50 In the embodiment shown in Figs. 8 and 9, the body portion 34 is shortened as compared with the body portion 14, and the flange 35 is larger 55 than the flange 16, the natural bias of the metal

being to force the flange 35 against the earth wall 17.

There is a lost motion connection generally indicated by 36 between the staff 37 and the body 34, and the staff is equipped with a contracting cup 38 telescoped over the body portion 34 and adapted to contract it as the device is about to be lifted from the cup. In this instance, the body is shown provided with three slits 39, which results in a corresponding number of curved members to be pressed against the wall 17.

In operation, the movement of the parts is much the same as the form first described, except that the expansion to fill the hole 17 is inherent in the body portion and the contraction is forced by the cup 38, which is the reverse of the arrangement shown in the first embodiment.

In the form shown in Figs. 10 and 11, the body portion 44 is substantially the same as the body portion 14, but a different expanding device is interposed between the staff 45 and the body.

The expander includes a sort of base ring 46 having a sliding fit on a reduced portion 47 of the staff. Pivoted on top of the ring 46 on pins 48 are arms 49 having upstanding curved members 50 to act upon the slit portions of the body 44 and spread the curved members 51 into contact with the wall 17 of the hole.

Those arms 49 are swung outwardly by a conical wedge 52 cooperating with inclined surfaces 53 on the arms, and the weight of the staff and flag pole furnishes sufficient force to effect the expansion.

Below the disk 48 the staff is provided with a contracting cone 54 having inclined surfaces 55 to cooperate with pins 56 in the arms 49 extending through slots 57 in the disk 48. When the staff is raised, the contractor 54 cooperates with the pins 56 to swing the arms inwardly and permit the body portion to collapse.

The operation is substantially automatic, for as the device is put into the cup the conical wedge 52 automatically expands the body portion, and as the staff is raised the contractor 54 automatically permits it to collapse.

The expanding and contracting of the body portion may be effected by a variety of other things, but the illustrations shown in the drawing are deemed sufficient for this disclosure.

The body portion may be made of a variety of materials, metallic and non-metallic. Thin stainless steel, now available under emergency restrictions, will be found satisfactory.

I claim:

1. In a device of the class described, a rounded body adapted to be received in a putting cup, relatively movable curved members on the body adapted to fit the earth above the cup, and operating means connected with the body and movable axially with respect thereto to cause relative movement of said curved members.

2. In a device of the class described, a rounded body adapted to be received in a putting cup, movable curved members on the body adapted to fit the earth above the cup, a staff operatively associated with said body and movable axially with respect thereto, and inclined operating elements carried by the staff and moving therewith to effect movement of the curved members.

3. In a device of the class described, a body adapted to be received in a putting cup and provided with relatively movable curved members adapted to fit the earth above the cup, a staff connected to the body for limited axial movement with respect thereto, and operating means on the staff adapted to cause relative movement of said members when the staff is moved relative to the body.

4. A golf hole protector comprising a staff adapted to be received in a putting cup, a plurality of curved members carried by the staff and adapted to fit the earth above the cup, said members being movable transversely of the staff between a position in which they engage the earth above the cup and a position in which they are spaced from the earth above the cup, and means operable by the staff for effecting such transverse movement of the members.

5. A golf hole protector of the type set forth in claim 4 in which the staff has limited axial movement with respect to the curved members and the means for effecting movement of the curved members is rendered operative during such limited axial movement of the staff.
